JOHN J. LYNG, OF YONKERS, NEW YORK, ASSIGNOR TO WESTERN ELECTRIC COMPANY,
OF NEW YORK, N. Y., A CORPORATION OF ILLINOIS.

SELECTIVE SIGNALING SYSTEM.

1,101,133.

Specification of Letters Patent. Patented June 23, 1914.

Application filed January 31, 1913. Serial No. 745,373.

To all whom it may concern:

Be it known that I, JOHN J. LYNG, citizen of the United States, residing at Yonkers, in the county of Westchester and State 5 of New York, have invented a certain new and useful Improvement in Selective Signaling Systems, of which the following is a full, clear, concise, and exact description.

This invention relates to signaling systems and more particularly to a telephone signaling system of the class wherein each of a plurality of stations on one line has a signaling device connected with the line wires which may be selectively operated, 10 each of said signaling devices being operable independently of the other devices on the same line.

The object of the invention is to provide a selective signaling system in which the 20 signaling device of any party on the line may be operated instantaneously and selectively in response to the operation of a calling key or switch at a main or sending station.

25 In a system embodying this invention there is located at each waystation on the line a local signal the circuit of which is controlled by two relays, the relays of each pair being severally operable by currents 30 over different circuits including the two line wires. The system depends for its selectivity of operation upon the positive operation or non-operation of these relays, that is to say, the combination of the apparatus 35 and circuits is such that no two sets or pairs of relays may be operated simultaneously. To provide for this the relays are made to respond to different strengths of currents, those operable over one of the circuits requiring currents of constantly increasing 40 strength from the sending station toward the end of the line, while those relays operable over the other of said circuits will respond to currents of decreasing strength 45 from the calling station outward, the relay in this circuit located at the end farthest from the calling station being operable with the minimum amount of current.

The drawing is a diagram of a circuit and 50 apparatus embodying this invention.

Referring to the drawing, 5 and 6 designate line wires with which are connected a sending or calling station A and a plurality of waystations B, C, D, E, F and G 55 respectively. Located at each of the way-

stations B, C, D, E, F and G is a pair of relays 14 and 15 controlling armatures 16 and 17 respectively. The relay 14 is connected in a bridge of the line wires 5 and 6 which bridge also includes resistances 20, 20 60 while the relay 15 is in a circuit to ground including a resistance 21, the circuit of said relay 15 being controlled by the armature 16 of the relay 14. The armature of the relay 15 controls a local circuit including a 65 source of energy 25 and a signal 26. The resistances 20, 20 in series with the relays 14, 15, although of the same value for each individual station, are tapered in value from the calling station A toward the end of the 70 line remote from the station, the resistances near the calling station being of low value and gradually increasing to a maximum value at the station farthest from the calling station. The resistances 21 in series 75 with the relays 15, 15 are likewise tapered in value from the calling station toward the end of the line remote from the calling station but in an inverse order to the resistances 20, 20—that is, the resistance 21 of 80 maximum value will be located at station B or that nearest the calling station A, the minimum value of 21 being at the end of the line remote from said station A. Certain numerical values are given these two groups 85 of resistances for purposes of illustration but it is to be understood that the application is not limited to the values given.

Located at the calling station A are a plurality of switch keys 30, 31, 32, 33, 34 and 35 90 corresponding in number to the waystations on the line. Each of said switch keys 30, 31, 32, 33, 34 and 35 is wired to connect battery with the line wires for operating the relays, a battery 36 for operating the bridged relays 95 being connected across the line wires 5 and 6 through a regulating resistance 38 divided into steps controlled by said switch keys. A battery 40 for operating the relays over the two line wires to ground is connected 100 from the center point of a high resistance 41 bridging the line through a resistance 42 divided into steps regulated by said switching keys 30, 31, 32, 33, 34 and 35. The wiring 105 of the switch keys 30, 31, 32, 33, 34 and 35, the batteries 36 and 40 and the resistances 38 and 42 is such that the operation of any key will send current over the two circuits in the proper amounts and directions to operate only a particular pair of relays 14, 15. 110

This will be more clearly seen by following the operation in signaling one or more of the stations on the line.

Assuming that it is desired to operate the signal 26 at station B. This will be accomplished by the operation of the key 30 which will close its contacts 50 and 51 to complete two circuits, one being from the one side of the battery 36, conductor 52, line wire 5, the 5 bridged relays 14, 14, line wire 6, conductor 53, the total of resistance 38, contact 50 of key 30 and conductor 54 to the opposite side of battery 36. Only sufficient current will flow in this path to operate the relay 14 at 10 station B. The other circuit closed by key 30 will be from ground at 55, through contact 51 of key 30, conductor 57, battery 40 to the middle point of resistance 41 to line wires 5 and 6 over which the current 15 passes in parallel to the middle point of the relay 14 at station B, through contact 58 closed by said relay 14 at the station B, conductor 59, relay 15 at station B, and the resistance 21 to ground. The full strength of 20 the battery 40 flows through this path but since the relay 14 at station B is the only one operated over the path first traced, there will be no circuit for any of the other relays 25 15. The operation of the relay 15 at station B will close the local circuit including the local signal 26 at this station B. In a like manner, if it is desired to signal any other station on the line, the key corresponding to this station will be depressed to apply the 30 proper current combinations to the two circuits to operate only a selected pair of relays.

It will be noted that although all of the 35 relays 14 at stations preceding any station on the line will be operated by the current which will operate the relay 14 at a selected station, the current in the path over which the relay 15 at the selected station is operated will be of sufficient strength only to operate that relay and the relays 15 at all succeeding stations beyond the selected one, thus making it impossible to call more than one station at a time.

While the relays are illustrated as the 40 polarized type, the invention may be worked with non-polarized relays, but it will be obvious that by the use of the polarized relays a system of much larger capacity can be obtained than is possible with non-polarized 45 relays. The method of wiring the switch keys when both polarities of battery are used for obtaining a selection will readily suggest itself to any one skilled in the art to which this invention pertains.

60 I claim:

1. In a party line selective signaling system, a pair of line wires, a sending station and a plurality of waystations connected therewith, a pair of relays located at each 65 of said waystations, the relays of each pair

being severally operable by currents over a metallic and a grounded circuit respectively including said line wires, means for rendering the relays of each pair responsive to current combinations of particular strengths over the two circuits, a signal at each of said waystations controlled by the relays thereat, and means at the calling station for impressing upon the circuits the current combination for operating any pair of relays. 75

2. In a party line selective signaling system, a pair of line wires, a sending station and a plurality of waystations connected therewith, a pair of relays located at each of said waystations, the relays of each pair being severally operable by currents over a metallic and a grounded circuit including said line wires, resistances in circuit with each relay of each pair rendering it responsive to a current of characteristic strength, a signal at each waystation controlled by the relays thereat, and means at the sending station for simultaneously applying currents to the two circuits of 90 strengths to operate a selected pair of relays. 85

3. In a party line selective signaling system, a pair of line wires, a sending station and a plurality of waystations connected therewith, a pair of relays located at each of said waystations, the relays of each pair being severally operable by currents over a metallic and grounded circuit including said line wires, resistances in circuit with each relay, the value of the resistance in circuit with the relays operable over one circuit increasing in value away from the sending station those in circuit with the relays operable over the other circuit increasing in 105 value toward the sending station, a signal at each of said waystations controlled by the relays thereat, and means at the sending station for applying currents to the circuits for operating a selected pair of relays. 110

4. In a party line selective signaling system, a pair of line wires, a sending station and a plurality of waystations connected therewith, a pair of relays located at each of said waystations, one operable over a metallic circuit including said line wires, the other over a grounded circuit including said line wires, resistances in circuit with each of said relays operated over said metallic circuit increasing in value from the sending station outward, resistances in circuit with each of said relays operating over said grounded circuit decreasing in value from the sending station outward, and means at the sending station for applying the current 120 to the line wires for operating any selected pair of relays. 125

5. In a party line selective signaling system, a pair of line wires, a sending station and a plurality of waystations connected 130

therewith, a pair of relays located at each of said waystations responsive to current over two paths both including said line wires, means in circuit with each of said 5 relays for determining the amount of current necessary for operating it, a source of operating current at said sending station, resistance at said sending station, and means at said sending station for connecting said 10 source of current with said circuits through

an amount of resistance to impress the proper amount of current upon said circuits to operate a selected pair of relays.

In witness whereof, I hereunto subscribe my name this 30th day of January A. D., 15 1913.

JOHN J. LYNG.
